US00D901457S

(12) **United States Design Patent** (10) **Patent No.:** **US D901,457 S**
(45) **Date of Patent:** **** Nov. 10, 2020**

(54) **WIRELESS HEADSET**

(71) Applicant: **Shenzhen Wireless Cloud Image Electronics Co., Ltd.**, Shenzhen (CN)

(72) Inventor: **Yong Zhang**, Shenzhen (CN)

(**) Term: **15 Years**

(21) Appl. No.: **29/736,767**

(22) Filed: **Jun. 3, 2020**

(51) **LOC (12) Cl.** **14-01**

(52) **U.S. Cl.**
USPC **D14/223**

FOREIGN PATENT DOCUMENTS

KR 300961710.0000 * 6/2018

Primary Examiner — Paula Allen Greene

(57) **CLAIM**

The ornamental design for a wireless headset, as shown and described.

DESCRIPTION

FIG. 1 is a first perspective view of a wireless headset showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the wireless headset in which the design is embodied that form no part of the claimed design.

1 Claim, 8 Drawing Sheets
